Attorney

UNITED STATES PATENT OFFICE.

JOHN W. CORNELIUS, OF KINGMAN, ARIZONA.

VARIABLE CONDENSER.

Application filed September 18, 1923. Serial No. 663,364.

To all whom it may concern:

Be it known that I, JOHN W. CORNELIUS, a citizen of the United States, residing at Kingman, in the county of Mohave and 5 State of Arizona, have invented certain new and useful Improvements in Variable Condensers, of which the following is a specification.

This invention relates to certain new and 10 useful improvements in variable condensers, particularly useful as a wave selector for radio apparatus.

The primary object of the invention is to generally simplify and improve devices of 15 the above kind whereby the same may meet with all of the requirements for a successful commercial use.

Another object of the invention is to provide a variable condenser characterized by 20 the fact that all of the plates thereof are fixed and assembled in such manner that they will not warp or readily short circuit.

Still another object of the invention is to provide a variable condenser which, in operation, provides for only placing such plates in circuit as are actually in use, and wherein the di-electric spacing for the condenser plates is constant.

Other objects will appear as the nature 30 of the invention is better understood, and the same consists in the novel form, combination and arrangement of parts herein-after more fully described, shown in the accompanying drawing and claimed.

35 In the drawing, wherein like reference characters indicate corresponding parts throughout the several views,

Figure 1 is a substantially central transverse sectional view of a variable condenser 40 constructed in accordance with the present invention,

Figure 2 is a sectional view taken substantially upon line 2—2 of Figure 1, and

45 Figure 3 is a perspective view of the removable plate contacting core.

Referring more in detail to the drawing, the preferred form of the invention embodies a suitable base 5 of relatively thick di-electric material upon which are centrally 50 arranged a pile of plates, alternate ones of which as indicated at 6 are of conducting material, and the remaining ones of which as indicated at 7 are of di-electric material, said plates being suitably rigidly secured in 55 contiguous relation and to the base plate 5 such as by means of bolts 8 extending

through the corners of the plates and surrounded by di-electric sleeves 9 that also extend through the corners of the plates. By means of this construction the plates are all 60 fixed so that a compact and rigid construction is had wherein danger of the plates warping is eliminated.

The plates 6 and 7 are all provided with central openings which register with each other to provide a passage in which is slidably mounted a contact carrying core 10 formed of suitable di-electric material and reduced at opposite sides. Suitably fastened upon the reduced opposite sides of the core 10 are contact plates 11 shaped to conform with the free edges of inwardly extending projections 12 provided on the conducting plates 6, which projections extend into the passage through the plates mentioned above. As shown clearly in Figure 1, alternate ones of the conducting plates have the projections 12 extending inwardly at opposite sides of the core 10 so that said conducting plates are divided into a series 70 of plus and minus or positive and negative plates.

The core 10 may be provided with a threaded stem as at 13 onto which may be threaded a suitable handle or knob, not shown, by means of which the core may be readily slid longitudinally in the passage through the plates, and the contact plates 11 of the core may be constructed as generally indicated at 14 for respective connection with the positive and negative wires 75 of the radio apparatus.

As the plates 11 engage alternate ones of the projections 12, it will be readily apparent that by adjusting the position of the 80 core 10, the capacity of the condenser may be conveniently regulated. In other words, alternate ones of the conducting plates 6 have projections 12 extending inwardly at 85 one side of the core 10 so as to have their inner edges engage one of the contact plates 11 of said core, while the remaining ones of said plates 6 have their projections or tongues 12 extending toward the opposite 90 side of the core 10 so that their inner edges engage the other contact plate 11 of the core. Thus, in operation, the current will flow from one contact plate 11 through the plates 6 which have tongues 12 engaged therewith, and then the current will pass 95 through the adjacent di-electric material to the other plates 6 which have tongues 12 in 100 105 110

engagement with the other contact plate 11. The capacity for which the condenser is adjusted therefore depends upon the number of plates having their tongues 12 engaged with the contacts 11.

It will thus be seen that I have provided a simple and durable form of variable condenser having all of the advantages and features enumerated above and constituting 10 a desirable article of manufacture capable of meeting with all of the requirements for a successful commercial use.

Minor changes may be made without departing from the spirit and scope of the 15 invention as claimed.

What I claim as new is:—

1. In a variable condenser, a pile of fixed plates, alternate ones of said plates being of conducting material, the remaining of said 20 plates being of di-electric material, all of said plates being provided with central openings that register for providing a passage through the pile of plates, said conducting plates having projections extending into said passage, the projections of alternate ones of said conducting plates extending from one side of the passage, and the projections of the remaining plates extending from the other side thereof, a core longitudinally 25 movable in the passage and having contact plates upon the sides thereof respectively engageable with the inner edges of the projections of alternate ones of the conducting plates, and means to facilitate adjustment 30 of the core within said passage.
2. In a variable condenser, a pile of fixed plates of conducting material separated by plates of di-electric material, all of said plates being provided with openings forming 35 a passage, a di-electric core movable in said passage and having electrically separated contacts, and means upon the conducting plates for placing the core carried contacts in electrical connection with alternate ones of said conducting plates, respectively.
3. In a variable condenser, a pile of plates, alternate ones of said plates being of

di-electric material, the remaining ones of said plates being of conducting material, 50 said plates having registering openings forming a passage therethrough, a core of di-electric material slidable in said passage and having electrically separated contact plates upon opposite sides thereof, inwardly extending projections upon alternate ones of the conducting plates engageable with one of said contact plates, and inwardly extending projections upon the remaining ones of said conducting plates for 60 making contact with the other of said contact plates.

4. In a variable condenser, a pile of plates, alternate ones of said plates being of di-electric material, the remaining ones 65 of said plates being of conducting material, said plates having registering openings forming a passage therethrough, a core of di-electric material slidable in said passage and having electrically separated contact plates upon opposite sides thereof, inwardly extending projections upon alternate ones of the conducting plates engageable with one of said contact plates, inwardly extending projections upon the remaining ones of said conducting plates for 70 making contact with the other of said contact plates, and means for facilitating connection of conductor wires to said contact plates.

5. A variable condenser comprising a base plate having a pile of plates rigidly mounted thereon in contiguous relation, alternate ones of said plates being of di-electric material, said plates having a passage there- 85 through, a core slidable in said passage, a pair of electrically insulated contact plates on said core, and means upon the conducting plates for respectively electrically connecting alternate ones thereof with the respective contact plates of the core upon predetermined adjustment of the latter.

In testimony whereof I affix my signature,

JOHN W. CORNELIUS.
